UNITED STATES PATENT OFFICE

LAWRENCE D. KOHLMAYER, OF INDIANAPOLIS, INDIANA

FILM FLAME STOP

Application filed August 29, 1929. Serial No. 389,271.

This invention relates to means for preventing the communication of fire from one compartment to another in a moving picture projecting machine due to the burning of 5 the film.

The principal object of the invention is to provide means that will arrest the travel of the flame along a strip of film automatically so as to prevent a more serious fire should 10 a major portion of the film become ignited.

Another object resides in providing such a fire arresting device that may not interfere with the free passage of the film through the machine and that may be easily threaded 15 when new film is to be employed.

These and other objects will become apparent in the following description of the invention as illustrated by the accompanying drawings, in which—

20 Fig. 1 is a diagrammatic side elevation in fragmentary form of the reel housing of a projecting machine;

Fig. 2, a top plan view of the fire arresting device;

25 Fig. 3, a side elevation of the device as shown in Fig. 2; and

Fig. 4, a vertical section on the line 4—4 in Fig. 2.

Like characters of reference indicate like 30 parts throughout the several views in the drawings.

Referring to Fig. 1, an upper reel 10 is shown as having a strip of film 11 leading downwardly therefrom across the compartment 12 and on to the reel 13. Both the reels 35 10 and 13 are enclosed in fire proof housings so that the only exposed length of film is that which is carried across the compartment 12 and into which a beam from a source of 40 light (not shown) is passed through the film 11 in order to project the picture in the usual and well known manner.

The greatest risk of igniting the film comes 45 when that portion of the film is carried across the compartment 12 so that it is desirable to prevent the flame from an ignited film therein from passing either upwardly or downwardly into either of the housings about the reel of film that may be contained 50 therein.

In order to prevent the passage of fire from this central compartment I provide an unique structure which is described as follows. I form a frame 14 substantially rectangular in shape with a horizontal attaching flange 15. A pair of rollers 16, 17 are pivotally retained in the frame on spaced apart parallel axes in the same vertical plane. These rollers have a slight space therebetween so that one does not contact the other 55 as either may be rotated. A floor 18 is provided to extend from near the bottom of the roller 16 across to the lower edges of the frame 14. These two rollers 16, 17 are set to one side of the center of the frame 14. 60

A second pair of rollers 19, 20 are carried within the frame 14 parallel to the rollers 16, 17, but instead of being carried on fixed axes, each roller 19 and 20 is separately carried between the arms of a U-shaped frame 21. Each of the frames 21 is pivotally secured in the frame 14 by means of a rod 22 passed thereacross through the legs near the lower edge and adjacent to the web of the members 21, see Fig. 4. These rods 22 are 65 fixed by their ends in the frame 14 and permit the frames 21 to rock therewith whereby the rollers 19, 20 may normally drop by gravity into contact respectively with the rollers 16 and 17. 70

All of the rollers 16, 17, 19 and 20 are slightly recessed across their central portions so that when the film 11 is passed therebetween, the film is contacted only along its outer edges so as to prevent scratching of the central portion of the film. The film 11 is threaded through between the rollers, Fig. 4, by inserting the film through a slot 24 vertically across the end of the frame 14 at the ends of the rollers and pulling the film upwardly slightly so as to cause the rollers 19, 20 to be rocked upwardly sufficiently to let the film 11 pass between those rollers and the rollers 16, 17. 80

Now should the film become ignited after 85 the film is drawn through between the rollers, the flame following the film is immediately stopped by reason of the rollers 19, 20 pressing against the softened film and compressing it against the rollers 16, 17, or should the 90 film 11 become ignited after it has passed 95 between the rollers 16, 17, the flame will be stopped by reason of the rollers 19, 20 pressing against the film 11 and compressing it against the rollers 16, 17, or should the 100

film be entirely severed, by the rollers 19, 20 dropping down into contact with the rollers 16, 17 as the end of the film passes thereacross so as to effectively bar the passage of a flame cap.

While I have here shown and described my invention in the one best form as now known to me, it is obvious that structural changes may be made in that form without departing from the spirit of the invention, and I therefore do not desire to be limited to that form, nor any more than may be required by the following claims.

I claim:

15. 1. A frame having a vertical passageway therethrough, a pair of rollers carried on fixed axes in said passageway, a second pair of rollers, a pair of frames each separating and rockably secured to said frame in said passageway and rotatably carrying said second rollers, said pair of frames being mounted in said first frame to permit said second rollers to swing downwardly by gravity toward and be stopped tangentially against said first rollers.
20. 2. A frame having a vertical passageway therethrough, a pair of rollers carried on fixed axes in said passageway, a second pair of rollers, a separate frame for each one of the last pair of rollers, each rockably secured to said first frame in said passageway and rotatably carrying said second rollers, said separate frames being mounted in said first frame to permit said second rollers to swing
25. 35. downwardly by gravity independently of each other toward and be stopped tangentially against said first rollers, said first frame having a film entry slot through one side substantially in a plane tangential to said first rollers.

40. In testimony whereof I affix my signature.
LAWRENCE D. KOHLMAYER.
